United States Patent Office

Des. 178,491
Patented Aug. 14, 1956

178,491

CINEMATOGRAPHIC CAMERA

Jacques Bolsey, New York, N. Y.

Application July 13, 1955, Serial No. 36,946

Term of patent 7 years

(Cl. D61—2)

FIG. 1

FIG. 2

FIG. 3

FIG. 4

FIG. 5

Figure 1 is a front elevational view of a cinematographic camera embodying my new design;

Figure 2 is an elevational view of one side thereof;

Figure 3 is a rear elevational view thereof;

Figure 4 is an elevational view of the other side thereof; and

Figure 5 is a top plan view thereof.

I claim:

The ornamental design for a cinematographic camera, as shown.
